LOCK

Charles Swilens, Chicago, Ill.

Application November 17, 1937, Serial No. 174,985

11 Claims. (Cl. 70—364)

The present invention relates to locks of the cylinder type.

The principal object of the invention is the provision of a lock embodying a cylindrical casing and a cylinder positioned therewithin, the cylinder to contain a plurality of tumblers adapted to engage the casing for locking the lock and for being disengaged therefrom for opening the lock.

A still further object of the present invention is the provision of a lock of the type indicated which would include a key post with a plurality of tumblers to be engaged by the key, and wherein means may be provided whereby the key post may rotate without opening the lock in case a wrong key is inserted within the key post for the purpose of unauthorized opening of the lock.

A still further object of the present invention is the provision of a lock embodying a cylindrical casing and a cylinder positioned for rotation therewithin, and a key post having a severable connection with the cylinder, so that when the cylinder is brought to a locked or unlocked position, said key post may become disconnected from the cylinder for further shifting the key post for withdrawing the key therefrom.

A still further object of the present invention is the provision of a lock which would include a cylinder and a key post jointed thereto by a severable connection, whereby the key post may be rotated without affecting the cylinder in the event the lock is attempted to be manipulated by a wrong key.

A still further object of the present invention is the provision of a lock of the type indicated which may be adapted to receive a number of attachments, one at a time, through the medium of which the lock may actuate a dead-bolt or latch-bolt for throwing the same into an open or locked position, and which dead-bolt or latch-bolt is at some distance from the lock proper.

A still further object of the present invention is the provision of a lock which would be substantially pick-proof.

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views;

Fig. 1 is a fragmentary elevational view of a

door with which the present lock is adapted to co-operate, showing the front end of the lock in elevation, and showing in dotted lines diagrammatically a bolt in engagement with the door frame which bolt is adapted to be actuated by the present lock;

Fig. 2 is a cross-sectional view through the lock, the view having been taken on line 2—2 of Fig. 1;

Fig. 3 is a transverse cross-sectional view on line 3—3 of Fig. 2, with the tumblers in locking position in the lock;

Fig. 4 is a similar view with the tumblers in unlocked position;

Fig. 5 is a longitudinal cross-sectional view through the lock with tumblers in unlocked position, the view having been taken substantially on line 5—5 of Fig. 4;

Fig. 6 is a longitudinal cross-sectional view with the tumblers in locking position with the lock, showing the key partially inserted into the lock;

Fig. 7 is a transverse cross-sectional view on line 7—7 of Fig. 6;

Fig. 8 is a similar view showing the rotation of the key post without affecting the lock;

Fig. 9 is a perspective elevational view of the key post;

Fig. 10 is a perspective elevational view of substantially one-half of the cylinder;

Fig. 11 is a longitudinal cross-sectional view, on a reduced scale, through the cylinder of the lock;

Fig. 12 is a rear end elevational view of the lock;

Fig. 13 is an elevational perspective view of a head co-operating with the present lock;

Fig. 14 is the rear end elevational view of the lock with an attachment affixed thereto for opening one type of bolt, latch or the like;

Fig. 15 is a perspective elevational view of the said attachment;

Fig. 16 is a perspective elevational view of one of the tumblers receivable within the cylinder of the lock;

Fig. 17 is a perspective elevational view of another attachment adapted to co-operate with the present lock;

Fig. 18 is a cross-sectional view through the door with the lock therein shown in elevation, illustrating the mode of affixing the attachment shown on Fig. 17 to the lock and the mode of its operation for opening another type of bolt, latch or the like;

Fig. 19 is an elevational perspective view of

another type of attachment adapted to co-operate with the present lock;

Fig. 20 is a cross-sectional view through the door showing the present lock in elevation therewithin with attachment shown on Fig. 19 in an operative position for actuating another type of a bolt or latch positioned within a casing which may be affixed to the door; and

Fig. 21 is a fragmentary elevational view of the door with the rear end of the lock in elevation, with the casing aforesaid removed.

Referring in detail to the present drawings there is shown a lock including a cylindrical casing 25, having an integrally formed face plate 26 at its front end, which face plate 26 by its rim portion extends beyond the periphery of said casing 25. Integrally formed with the rim portion of said plate 26, and at its rear face is a rearwardly extending pin 27 which may be driven into the door for preventing the rotation of the casing as illustrated in Figs. 18 and 20. At two oppositely disposed points of the outer periphery of said casing 25 the same may be provided with recesses or channels 28 for receiving therewithin screws 29 driven through door 30, which arrangement constitutes an additional means for preventing the rotation of casing 25 within the door.

The rear end of said casing 25 is reduced and is exteriorly threaded as at 31 for receiving in threaded engagement cap 32.

The lock further includes a key post, best shown in Fig. 9, which includes, at its front end head 33 and flange 34, the latter two being adapted to be received within a correspondingly shaped bore 35 made centrally of face plate 26, said head 33 and flange 34 being receivable within said bore 35 from the rear of cylinder 25, and when once in an operative position, shown in Figs. 2 and 4, said key post cannot be withdrawn from the lock 40 forwardly thereof and through plate 26, because flange 34 prevents forward shifting movement of said key post.

Integrally formed with said head 33 and rearwardly extending therefrom is a cylindrical spindle generally indicated by 36 in Fig. 9, and which includes a hollowed portion 37 and solid portion 38. Integrally formed with the rear end of said spindle 36 is a collar 39 from which extends a cam lug 40, the latter being substantially square in transverse cross-section with its corner edges filed off or tapered as at 41.

Made in head 33 is a key slot 42 communicating with the slot in spindle 36 and defined by its portions 37 and 38. Said slot 42 and spindle 36 are adapted to receive key 43, the same being provided longitudinally and centrally thereof and on one of its faces, with ridge 44, key slot 42 being correspondingly shaped to receive and accommodate said ridge 44 during insertion of the key thereto, and portion 37 being channelled to receive said ridge 44 therewithin, as is clearly seen in Fig. 4. This arrangement prevents shifting of key 43 on the plane co-extensive with the plane of said key, when the same remains within the lock, and also constitutes a guiding means for the key during the insertion thereof into the lock. Said key 43 is provided on both of its edges with a plurality of notches or teeth 45 which are adapted to engage the tumblers hereinafter described.

The cylinder of the lock is best shown in Figs. 10 and 11. A pair of uniformly spaced cylindrical segmental blocks 46 are connected at their rear end by a head generally indicated by 47. The inner parallel faces of said segmental blocks

46 are provided with alternate grooves 48 which constitute seats for coil springs 49 as is seen in Figs. 3 and 4. One of the ends of said grooves 48 are open through the peripheral portions of said blocks 46 and portions of said segmental blocks 46 at the opposite ends of said grooves 48 constitute seats which limit the movement in that direction of said springs 49. These grooves 48 in each of said segmental blocks 46 are uniformly spaced by solid portions 50 of said blocks, and the width of said spaces between the blocks corresponds to the width of said grooves 48. Where there is the spacing portion of the block in one of the said blocks 46 at the opposite block 46 there remains a groove 48.

Head 47 of the cylinder is provided with a cross shaped recess 51 which, by its ends defines four uniformly spaced blocks 52 each of which has a sector-like shape on transverse cross-section through said head 47. The central portion 20 of said head 47 adjacent the center of said cross recess 51 is provided with a round opening 53 for receiving therewithin collar 39 of the key post as is clearly seen in Figs. 2, 5 and 6. In the operative association of the key post with the lock 25 the cam lug 40 will remain in the center of said cross recess 51. A pair of oppositely disposed blocks 52 are provided with a bore 54 in each, for the purposes hereinafter stated.

Receivable within each end of the cross recess 51 is a box 55, closed at its inner end, but open at its outer end for receiving coil spring 56, which bears against the closed end of said box 55 by one of its ends, while by the other end each of said coil springs 56 bears against the adjacent wall of said head 47 and defined by the cross recess 51. Receivable within the center of said cross recess 51 and among the four boxes 55 is cam lug 40. Normally, through the medium of said boxes 55, springs 56 exert pressure upon the faces of said cam lug 40 for normally maintaining the same in position for normally preventing the rotary movement of the said key post. Co-operating with the lock is head 57, best shown in Fig. 13, which is of an annular shape, with its peripheral side tapered 45 as at 58 to be engaged by a constricted mouth 59 made centrally in cap 32. Said head 57 at its rear face is provided with a pair of lugs 60 which are insertable within bores 54, by means of which arrangement said head 57 is rigidly 50 affixed to the cylinder of the lock and whereby it is adapted to rotate with the cylinder. The outer rear end of said head 57 is provided with an outwardly extending pin 61, which is positioned adjacent the edge of said outer face of head 57, and is also provided with a threaded bore 62. Centrally thereof said head 57 has a channel 63 for the purpose hereinafter described.

Receivable within the cylinder of the lock is a plurality of tumblers 64, one of which is best shown in Fig. 16. Each of said tumblers is made of flat metallic material and is of the thickness corresponding to the width of grooves 48 and of the spaces between said grooves. Each of said tumblers 64 has an oblong shape, and the width 65 thereof defined by its straight side edges 66 corresponds to the space defined by the inner faces of the segmental blocks 46. The remaining two oppositely disposed edges of each of the tumblers 64 are arcuate as at 66, and in continuation, conform to the peripheral arc of the outer faces of segmental blocks 46, as is clearly seen in Fig. 3. Extending from each arcuate edge 66 of tumblers 64, and from a central point thereof, is lug 67. Extending laterally from each tumbler 64, and 75

adjacent one termination of the side edge thereof, is shoulder 68. Each of said tumblers 64 is further provided with a substantially oval opening 69, the longer extent of which is in transverse relation with the tumbler. Said opening 69 defines an operative inner edge 70 of the tumbler and an inoperative edge 71 thereof, both in an opposite relative juxtaposition and both in a substantially transverse relation with the tumbler. The operative edge 70 and inoperative edge 71 defined by said opening 69, are substantially in parallel relation with respect to the adjacent, respective outer arcuate end edges 66 of the tumbler. The operative edge 70 defined by said opening 69 lies at an end in said tumbler 64 opposite to that end from which shoulder 68 extends, while the inoperative edge 71 defined by said opening 69 is at that end of tumbler 64 from which said shoulder 68 extends.

All of the tumblers are of like construction hereinabove described, excepting that the position of opening 69 varies in all of the tumblers. In some of said tumblers 64 said opening 69, although of equal dimension, may be in a nearer proximity to one arcuate end edge 66 of the tumbler, while in others it may be farther removed therefrom, all depending upon the distance of teeth or notches 45 from the center of the key to operate the tumblers, as will be later apparent.

Said tumblers 64 in an operative association with the cylinder of the lock, are receivable within the space defined by the parallel inner faces of the segmental blocks 46. Although the lock disclosed herein may comprise an unlimited number of tumblers the lock illustrated in the drawings is shown to contain eight tumblers. Four of the tumblers have their one straight side edges 65 facing grooves 48 with the shoulders 68 thereof entering the openings of said grooves or pockets 48 made in one of the said segmental blocks 46, as is seen in Fig. 3. These tumblers will be insertable from one open side of the space defined by straight parallel walls of the two segmental blocks 46. In these tumblers the opposite straight edges 65 contact with spaces 50 defined by the opposite segmental blocks 46. The remaining alternate tumblers 64 are receivable into the space in the lock cylinder defined by the two inner straight parallel faces of segmental blocks 46 from the opposite end thereof. In these latter tumblers, shoulder 68 will enter the open ends of pockets 48 at points opposite from those within which the first named tumblers have entered. The relative alternate position of the two series of tumblers is clearly seen in Figs. 2, 3 and 6.

From the above description it will be seen that each tumbler 64 is actuated by its spring 49 remaining within pocket 48, said spring bearing against shoulder 68 and urging each tumbler to shift outwardly of the lock cylinder.

Casing 25 is provided with a pair of oppositely disposed recesses 72 within which lugs 67 of tumblers 64 are adapted to fit. Said recesses 72 are made on the inner peripheral side of casing 25 and run the entire length thereof. Figs. 2 and 3 show the lock in a locked position with lugs 67 of tumblers 64, at the end of tumbler adjacent shoulder 68, within one of the recesses 72. Lugs 67 of alternate four tumblers 64 are within one recess 72, whereas lugs 67 of the remaining alternate tumblers are within an oppositely disposed recess 72, as is clearly seen in Fig. 2. When in that locked position of the tumblers it is impossible to rotate the cylinder, including the tumblers, segmental blocks 46, cylinder head 47, and with the latter

head 57. Through the medium of said lugs 67 remaining within oppositely disposed recesses 72, the cylinder of the lock, including the parts thereof last hereinabove mentioned, will remain interlocked with the cylindrical casing 25. There is no rigid permanent interengagement between the key post and the lock cylinder aforesaid. Neither is there any rigid engagement between any edges 70 and 71 of the tumblers with the spindle 36 of the key post. Thus it is possible to insert a wrong key into the key slot 42 and rotate the key post without in any manner affecting tumblers 64 or disengaging them from the cylindrical casing 25. Also partial insertion of a right key into key slot 42, as shown in Fig. 6, will rotate the key post, but will not unlock the lock. Rotation of the key post will likewise cause the shifting of cam lug 40 which bearing against the closed faces of boxes 55 will cause the depression of coil springs 56. Said springs bearing against the corner edges 20 of cam lug 40 as shown in Fig. 8, facilitate the assumption of the proper position of cam lug 40 as illustrated in Fig. 7.

Assuming that the tumblers are in a locked position in the lock, as shown in Figs. 2 and 3, the passage of any key capable for insertion within slot 42 will be unobstructed so far as the slot within spindle 36 is concerned, by virtue of the fact that the end edges defined by openings 69 of tumblers 64, are far removed from spindle 36, 30 regardless as to whether the tumblers are in a locking engagement with cylindrical casing 25.

When a proper key has been inserted within the key post, notches or teeth 45 will engage the operative edges 70 of the several tumblers when the key is turned forty-five degrees. Said teeth or notches 45 of the key bearing against operative edges 70 of the several tumblers will shift said tumblers against the tension of coil springs 49 to bring lugs 67 of the tumblers out of recesses 72. When said lugs 67 have been brought out from said recesses 72, further shifting of the key will rotate the entire cylinder mechanism, including said tumblers 64, segmental blocks 46, and head 47 by virtue of engagement of the key post with said head 47 through the medium of cam lug 40, boxes 55 and springs 56. When said lugs 67 of the two alternate series of tumblers 64 are out of engagement with the respective recesses 72, and the key is further rotatably shifted, said lugs 67 will ride upon the peripheral inner face of casing 25 as is clearly seen in Fig. 4.

Thus, from the hereinabove description it will be seen that there is a two-fold purpose and action of cam lug 40. First, when an unauthorized person attempts to open the lock without a proper key, having inserted a wrong key and attempting to open the lock, an unauthorized person will naturally revolve the key. With the turning of the key a rotary shifting movement will be imparted to the key post including head 36, spindle 36 and cam lug 40. In this case cam lug 40, as it rotates simply serves to depress springs 56, as shown in Fig. 8, to again assume normal position shown in Fig. 7. Thus, in this instance cam lug 40, boxes 55 and springs 56 serve as means to facilitate disengagement between key post and the cylinder of the lock, without affecting in any manner the locked engagement between the cylinder and cylindrical casing 25 through the medium of lugs 67 of the tumblers. Second, cam lug 40 and springs 56 serve to positively engage the key post with the cylinder of the lock to rotate the latter when the lugs 67 have been shifted by a proper key by imparting pressure thereof at 75

the operative edges 70 of the tumblers for shifting the latter. It is noted that springs 56 exert a sufficiently strong pressure upon four sides of cam lug 40 not only to maintain the engagement 5 of the key post with the lock cylinder for the purpose of rotating the latter within cylindrical casing 25, but also for the purpose of rotating head 57 and shifting its lug 61 or any one of the attachments hereinafter described for locking or 10 unlocking various bolt or latch devices.

It is further observed that normally, when the tumblers remain in a locking position with respect to the cylindrical casing 25, it is possible to insert the key within key slot 42 and spindle 36 until its inner end will hit the bottom of cam lug 40, as is seen in Fig. 3, the end edges defined by openings 69 in the several tumblers not obstructing in any manner insertion of the key. Immediately upon insertion of the key for the 15 purpose of operating the tumblers the key will assume a transverse relation with respect to the tumblers as is apparent from Fig. 3. On imparting a twist to the key of forty-five degrees, key will assume a longitudinal position with respect 20 to all of the tumblers, its notches or teeth 45 will ride upon the operative edges 70 to shift said tumblers 64 against the tension of springs 49, simultaneously depressing said springs in order to disengage lugs 67 of the tumblers from the respective recesses 72. When said longitudinal position of the key with respect to tumblers 67 is 25 maintained, the key being in a strong frictional contact with said operative edges 70 of the tumblers by virtue of the pressure exerted therebetween by springs 49, the key is turned further and thereby the cylinder of the lock is rotated by virtue of the engagement between the key post and said cylinder through the medium of cam lug 40 and springs 56 as hereinabove described, until lugs 67 come in alignment with the remaining pair of recesses 72. When said lugs have reached that latter position, at that very same point bolt 73 has been fully shifted into the door frame 74 through the medium of engagement thereof by pin 61 upon head 57. When bolt 73 is in that locked engagement with the door frame 74, pin 61 necessarily cannot be further shifted and head 57 cannot be rotated. Further turning of the key at that juncture will 30 not further rotate the cylinder of the lock, although it will be possible to further rotate the key and key post to bring about the disengagement of the latter with said cylinder through the medium of cam lug 40 and springs 56.

55 This latter operation of the key will cause the disengagement of the key from the operative edges 70 of the several tumblers and the lugs will instantly spring into recesses 72 on the horizontal plane of Fig. 4, bringing about positive locking between the cylinder of the lock and the cylindrical casing 25, springs 49 pressing against shoulder 68 facilitating the shifting of the alternate tumblers into the opposite directions to spring lugs 67 into the horizontal pair of recesses 65 72 as seen from Fig. 4. Said further shifting of the key last hereinabove mentioned will bring slot 42 as well as the slot within spindle 36 to a transverse relation with the tumblers and the key may then be withdrawn. From that locked 70 engagement between the lock cylinder and cylindrical casing 25 last hereinabove described, the key is shifted again forty-five degrees, and this shifting will cause rotation of key post and cam lug 40 also forty-five degrees, during which time cam lug 40 will bear against boxes 55 and springs

56 and will pass through the position illustrated in Fig. 8 to assume normal position shown in Fig. 7. The cam action between cam lug 40 and springs 56 also facilitates the bringing of key post or rather the slot within spindle 36 to a transverse position relative to the several tumblers so that the key may be withdrawn.

To withdraw bolt 73 from door frame 74 a reverse operation from that hereinabove described is resorted to in order to disengage lugs 67 of the tumblers from within a pair of horizontally disposed recesses 72 and to shift the same in the path of vertically disposed recesses 72. For this purpose the key, of course, is inserted as before, and is turned in an opposite direction, simultaneously cam lug 40 is rotated against the tension of springs 56 until key will assume a longitudinal position with respect to the tumblers, that is the position on a horizontal plane running through the pair of horizontal recesses 72 and when said lugs 67 were thus disengaged from said recesses 72 the lock cylinder is rotated into counterclockwise direction by virtue of the engagement of the key post with the said cylinder through the medium of said cam lug 40 and springs 56 until lugs 67 come into the path of the pair of vertical recesses 72. At this point it is assumed that pin 61 has fully shifted bolt 73 into an unlocked position and out of engagement with door frame 74 and said pin 61 is incapable of further shifting. Thus, by virtue of engagement of said pin 61 with bolt 73 and the cylinder of the lock, the latter may not be further rotated. By continuing further shifting of the key for forty-five degrees more the key will become disengaged from tumblers 64, lugs 67 will fall into the pair of vertical recesses 72 due to the action of springs 49, and further shifting of the key will rotate key post and spindle 36 and revolve cam lug 40 against the tension of springs 56, until the key 40 is brought to a horizontal plane and into a transverse relation with the tumblers, a position shown in Fig. 3, at which moment the key may be withdrawn due to the lack of engagement thereof with the operative edges 70 of the tumblers.

From the hereinabove description it will be seen that the cam action of cam lug 40 and springs 56 has several important objects in view. It permits positive engagement between the key post and the lock cylinder for rotating the latter when tumblers 64 remain out of engagement with casing 25, for the purpose of shifting pin 61 into a locked or unlocked position for shifting bolt 73 into a locked or unlocked position with relation to the door. It permits ready disengagement of the key post from the lock cylinder for the purpose of rotating the key post independently of the cylinder in order to disengage the key from the tumblers for withdrawing the key from the key slot. And finally, it permits an independent rotation of the key post, and this regardless as to whether the lock remains in a locked or an unlocked position relative to pin 61 and bolt 73. This last mentioned action of the cam mechanism renders the lock wholly unsuitable for the purpose of unauthorized picking or interference. Not only this, but it prevents damage of the lock which may readily occur due to attempts of unauthorized opening by a wrong key. Locks in which the parts are rigid and stationary when the lock remains in a locked position facilitate to a greater degree the unauthorized opening than would the present locks

facilitate and this being entirely due to the key post which is rotatable under all conditions.

It is further observed that the length of each tumbler 64 including lugs 67 may either substantially equal to the diameter of the cylindrical casing 25, or may be shorter in length than the diameter so that when lug 67 of tumbler 64 is dislodged from recess 72 by the action of a proper tooth or notch 45 of key 43, the opposite lug 67 will either remain substantially on the plane of the inner periphery of casing 25 or will be at some distance therefrom. In order, therefore, that one single tooth or notch 45 of key 43 may be proper for successfully working upon the operative edge 70 of the respective tumbler 64 for withdrawing lug 67 of tumbler 64, at the opposite end thereof, from recess 72 within which said lug remains, without, at the same time, shifting the opposite lug 67 into the opposite recess 72, the width of the key at that point, from the axial center of the key laterally to the termination of said notch or tooth 45, must be such as to equal, in conjunction with the width of the tumbler defined by the center of the operative edge 70 and the outer termination of the adjacent lug 67, the radius of the lock cylinder. This arrangement is clearly seen from Figs. 4 and 5. The point at the edge of the key oppositely disposed to the operative notch or tooth 45 must be considerably reduced by filing so that the opposite inoperative edge 71 defined by opening 69 of the tumbler may preferably not come in contact with the key during the shifting of the tumbler against pressure of spring 49 when the tooth or notch 45 of the key remains in engagement with the operative edge 70 of the tumbler. It is also observed that the operative edges 70 of the tumblers bear against and contact with spindle 36, as is clearly seen in Figs. 2 and 3, when tumbler 64 is in engagement with casing 25 through lug 67.

From the hereinabove description it will be seen that the particular combination of the several tumblers, whereby the lock may be operated by a particular key, depends upon the relative placing of openings 69 with respect to the longitudinal center of the lock and longitudinally of each tumbler. The placing of opening 69 in each tumbler 64 may be varied, thereby varying the distances between operative edge 70 and the outer termination of the adjacent lug 67 of each tumbler 64, and this variable factor will in turn vary the notches or teeth 45 of the lock so far as the distances of the outer edges thereof from the axial center of the key are concerned. Measuring the distances defined by the operative edge 70 of each tumbler 64 from the outer termination of the adjacent lug 67 will pre-determine just how long the particular tooth or notch 45 of key 43 should be made in the key blank. Following this example with each tumbler 64 will pre-determine the sizes of all of said teeth or notches 45 upon the key prior to striking them from a key blank.

Since some of the forward notches or teeth 45 of the key are more deeply cut than the notches or teeth at the rearward end of key 43, it follows that when said key engages all of the tumblers 64 of two alternate series thereof, some of the tumblers may remain in a transverse path of the rearward notches 45, thereby preventing the withdrawal of the key from the lock. It is only at the time when lugs 67 remain within the respective recesses 72 that it is possible to with-

draw the key from or to insert the same into the lock, as is clearly seen in Fig. 3.

It should be noted that the complete procedure of locking or unlocking of bolt 73 is pre-determined with the operation of the lock so that the two actions of the said bolt may coincide with lugs 67 of the tumblers coming into the path of the two pairs of oppositely disposed recesses 72, respectively. This timing of bolt 73 with lugs 67 coming into the path of one or the other pair of recesses 72 should be pre-determined as otherwise lugs 67 may fail to be engaged with cylindrical casing 25 through the medium of said recesses 72 or in other words there may be failure of properly locking the lock.

Since the lock herein disclosed is capable of use in connection with various locking and latching devices and in connection with various objects such as doors, safes, trunks, automobile doors, etc., various attachments may be used in connection with the lock, and the attachments shown in the drawings are for the purposes of illustration and the showing thereof does not contemplate the exclusion of others. In Figs. 14 and 15 there is an attachment embodying a plate 75 having an aperture 76 and a screw opening 77. Said plate 75 is seated over the outer face of head 57, pin 61 entering said aperture 76, screw 78 affixing said plate 75 to said head 57, said screw 78 passing through screw opening 77 in said plate and engaging the head 57 through the medium of threaded bore 62. One end of said plate 75 is farther removed from the center of the lock, as seen in Fig. 14 and carries an outwardly projecting pin 79, the operation of which is similar to the operation of pin 61 in connection with bolt 73. This latter pin 79 being farther removed from the center of the lock cylinder affords a greater throw and is capable of operating a bolt or latch of a varied type requiring a greater throw for shifting the same into an open or locked position.

Another attachment is shown in Fig. 17, which consists of an oblong square rod 80 provided with an integral head 81 at one of its ends. This rod 80 is affixed to head 57 by inserting head 81 within channel 63. This is accomplished prior to engaging said head 57 with the lock cylinder through the medium of lugs 60, by inserting said head 81 into said channel 63 laterally of said head 57. Thereupon said head 57 is placed into its operative position in conjunction with the lock cylinder, shown in Figs. 2, 5 and 6, and thereupon cap 32 is applied to the rear end of cylindrical casing 25. The face of constricted mouth 59 prevents shifting of head 81 out of engagement with head 57. This attachment, consisting of said rod 80 is adapted to rotate on a line co-extensively of the axial center of the lock casing, as is apparent from Fig. 18. Rod 80 may be of varying lengths depending on the distance of the bolt within casing 82' from the lock proper. This attachment particularly is best adapted for use where the bolt to be controlled by the lock is far removed therefrom, and also in cases where the wall within which the lock is insertable is thicker than the length of the lock, as is clearly seen in Fig. 18.

Another attachment illustrated in Fig. 19 consists of an oblong plate 82 having at one of its ends an integral cylindrical transverse extension 83 which is receivable within channel 63 of head 57. Extension 83 received within said channel 63 with cap 32 in operative position will be incapable of disengagement from the lock, or

more specifically from head 57, in view of the wall of constricted mouth 59 of cap 32 preventing its displacement, similarly as in the case of head 81 of rod 80. When said plate 82 is in an operative association with the lock it is capable of rotary shifting movement on a line co-axial with the longitudinal center of the lock.

As another exemplification of the use of the lock, Fig. 20 shows a bolt or latch casing 84 as being affixed to the inner face of door or wall 30, into which plate 82 is adapted to enter, as indicated by dotted lines, for engaging bolt, latch or any other locking device for actuating the same.

Figs. 20 and 21 illustrate an additional mode of affixing the lock herein disclosed to a comparatively thick door or wall. This mode contemplates making bore 85 to which the lock, including casing 25 and cap 32 may be inserted from the front end thereof. The rear end of said bore 85 is adapted to receive an annular plate 86 having an inwardly tapered edge as at 87 to enter the correspondingly shaped mouth of said bore 85, by virtue of which arrangement said plate 86 remains countersunk within door or wall 30 and flush with its inner face.

Plate 86 is further provided with a plurality of inwardly tapered openings to form seats for heads 88 of screws 89. The other inner ends of screws 89 engage cap 32 and casing 25 through threaded bores 90.

It is also observed that while the degree or extent of shifting of bolt 73 of Fig. 1 into its locked or unlocked position within the door will be accomplished by rotating the lock cylinder within casing 25 to forty-five degrees, it is obvious that plate 75 having a greater degree of throw may require rotation of the cylinder within casing 25 to ninety degrees. The attachments illustrated in Figs. 17 to 21, both inclusive, may even require one or more revolutions of the cylinder within casing 25 before they have fully completed their operation to bring their respective bolt or latching devices into an open or closed position. It is not important just how many degrees of rotation of the lock cylinder within casing 25 must be resorted to in order to bring the bolt or latching device into its locked or opened position, but it is important that when the same has been brought to one or another position lugs 67 of the several tumblers should, at that particular moment be in alignment with one or the other pair of recesses 72 so that at that particular moment no further rotation of the cylinder within casing 25 may be required, but that the further rotary shifting movement of the key may release tumblers 64 in order to bring their lugs 67 into recesses 72. In other words, when the key was brought to the point in its turning at which the same is incapable of further rotating the lock cylinder, and the further pressure on the key springs the cam mechanism, including cam lug 40 and springs 56 to impart an independent rotary movement to the key post, this will signify that the bolt or latching device has been completely shifted to its locked or unlocked position and the same cannot be shifted further.

It is obvious that some bolt or latching device may require less than forty-five degrees of rotation of the cylinder within casing 25. In that case one or more additional pairs of recesses 72 may be provided on the peripheral side of casing 25.

To assemble the several parts of the lock, first, the tumblers are placed in position between the

two segmental blocks 46. Thereupon key post by its cam lug 40 is inserted through the front end of the cylinder and is manipulated until the same passes through all openings 69 of the tumblers. When cam lug 40 remains within the center of the cross recess 51, springs 56 with their boxes 55 are inserted within the remaining four portions of said cross opening 51. Thereupon the cylinder is inserted into casing 25 and through the rear end of the latter, until head 33 is brought into bore 35. Thereupon head 57 is connected to the rear end of the cylinder by means of lugs 60, and thereupon cap 32 is applied.

So that the first spring 49, the one positioned at the frontmost part of the cylinder may not come directly in contact with the face plate 26 or with flange 34 of head 33 of the key post in the assembled condition of the lock, as the same thus coming in contact would gradually wear out, a suitable protecting means may be provided such as suitably shaped plate overlying the front end of segmental blocks 46 and inclosing that spring 49 within its respective groove 48. Or, a body portion may be left in the said segmental block 46 to overlie said spring for accomplishing the said object.

While there is described herein a preferred embodiment of the present invention, it is nevertheless to be understood that minor changes may be made therein without departing from the spirit and scope of the invention as claimed.

What I claim as new is:

1. A lock comprising a casing, a cylinder within said casing, a plurality of tumblers within said cylinder normally engaging said casing, a key post within said cylinder, said key post being adapted to receive a key to engage said tumblers for disengaging the same from said casing, and a severable connection between said key post and said cylinder operable by said key post upon actuation thereof by the key.

2. A lock comprising a casing, a cylinder within said casing, a plurality of tumblers within said cylinder normally engaging said casing, a key post within said cylinder adapted to receive a key for actuating said tumblers for disengaging the same from said casing, said cylinder being adapted to be rotated within said casing by the key through the medium of said key post when said key has actuated said tumblers and has disengaged the same from said casing, and a severable connection between said key post and said cylinder for permitting disengagement between said key post and said cylinder for permitting rotation of said key post independently of said cylinder when said key has failed to disengage all of said tumblers from said casing.

3. A lock comprising a casing, a cylinder within said casing and adapted for rotary movement therewithin, a plurality of tumblers in said cylinder normally engaging said casing for maintaining said cylinder against rotation within said casing, a key post within said cylinder adapted to receive a key for actuating said tumblers for disengaging the same from said casing for permitting rotation of said cylinder within said casing for bringing said cylinder into a locked or unlocked position, and a severable connection between said key post and said cylinder, said severable connection permitting continued rotation of said key post within said cylinder and independently thereof when said cylinder has been brought to either locked or unlocked position within said casing.

4. A lock comprising a casing, a cylinder within

- said casing, said cylinder being adapted to rotate within said casing into a locked or unlocked position, a plurality of tumblers within said cylinder adapted to normally engage said casing for 5 providing positive engagement between said casing and said cylinder when the latter is either in a locked or unlocked position, a key post within said cylinder provided with a key slot permitting insertion of a key therewithin for engaging said 10 tumblers for actuating the latter out of engagement with said casing, and a severable connection between said key post and said cylinder, said key post being adapted to impart rotary movement to said cylinder through the medium of 15 said connection when the key is rotated upon the disengagement of said tumblers from said casing, said connection being adapted to disengage said key post from said cylinder when said cylinder was brought to either locked or unlocked position 20 for permitting continued rotation of said key post independently of said cylinder.
5. A lock comprising a casing, a cylinder within said casing, means for engaging said cylinder with said casing when the former remains in a 25 locked position, a key post within said cylinder, and a severable connection between said key post and said cylinder, said key post being adapted to receive a key for actuating said means and for imparting rotary movement to said key post and 30 said cylinder through said severable connection for shifting said cylinder within said casing to an unlocked position, said connection being adapted to release said key post from said cylinder for permitting continued rotary movement 35 of said key post independently of said cylinder when said cylinder has been brought to a locked or unlocked position.
6. In a lock including a casing, a cylinder, a key post adapted to receive a key, a yieldable and 40 severable connection between the key post and the cylinder for permitting rotation of the cylinder within said casing on imparting a rotary movement to the key post by the key to shift the cylinder into a locked or unlocked position within 45 the casing and for permitting an independent rotary movement of the key post when said cylinder has been brought into a locked position with respect to the casing, comprising a camming device in said cylinder.
- 50 7. In a lock including a casing, a cylinder, a key post adapted to receive a key, a yieldable and severable connection between the key post and the cylinder for permitting rotation of the cylinder within said casing on imparting a rotary

movement to the key post by the key to shift the cylinder into a locked or unlocked position within the casing and for permitting an independent rotary movement of the key post when said cylinder has been brought into a locked position with respect to the casing, comprising a cam lug in said key post and tensioning means in said cylinder disengageably contacting with said cam lug. 5

8. In a lock including a casing, a cylinder and a key post and of the type wherein said cylinder is adapted for rotation within the casing for bringing said cylinder into a locked or unlocked position with respect to the said casing, a disengageable connection between said cylinder and said key post, and means for severing said connection when said cylinder has been brought to a locked position with respect to the casing. 10

9. A lock comprising a casing, a cylinder within said casing, means for normally engaging said cylinder with said casing, a key post within said cylinder, said key post being adapted to receive a key for actuating said means for disengaging said cylinder from said casing, and a severable connection between said key post and said cylinder operable by said key post upon actuation 15 thereof by the key. 20

10. A lock comprising a casing, a cylinder within said casing, means for normally engaging said cylinder with said casing, a key post within said cylinder, said key post being adapted to receive a key for actuating said means for disengaging said cylinder from said casing and for rotating said cylinder, and disengageable connecting means between said key post and said cylinder, said connecting means being adapted to disengage for permitting actuation of the key post by the key independently of said cylinder upon actuation of said means by the key. 30

11. A lock comprising a casing, a cylinder within said casing, means for interlocking said cylinder with said casing, a key post within said cylinder, said key post being adapted to receive a key for actuating said means for disengaging said cylinder from said casing and for relative shifting of said cylinder with respect to said casing, and connecting means between said key post and said cylinder, said connecting means being adapted to disengage for permitting independent shifting of said key post with respect to 40 said cylinder by the key when the key has actuated said interlocking means. 45

CHARLES SWILENS.
